(57) **CLAIM**

The ornamental design for a garment carrier case with insert, as shown and described.

DESCRIPTION

FIG. 1 is a front view of the garment carrier case with insert incorporating a design according to the invention.

FIG. 2 is a rear view of the garment carrier case with insert.

FIG. 3 is a left side elevation view of the garment carrier case with insert.

FIG. 4 is a right side elevation view of the garment carrier case with insert.

FIG. 5 is a top plan view of the garment carrier case with insert.

FIG. 6 is a bottom plan view of the garment carrier case with insert.

FIG. 7 is an exploded perspective view of the garment carrier case and the insert.

FIG. 8 is top view of the garment carrier case with insert.

FIG. 9 is a rear perspective view of the insert with the clip in a folded position.

FIG. 10 a rear perspective view of the insert with the clip in an extended position.

FIG. 11 is a rear view of the insert with the clip folded.

FIG. 12 is a front view of the insert with the clip folded.

FIG. 13 is a left side view of the insert with the clip folded.

FIG. 14 is a right side view of the insert with the clip folded.

FIG. 15 is a top plan view of the insert with the clip folded; and,

FIG. 16 is a bottom plan view of the insert with the clip folded. The insert is shown separately for convenience of illustration.
